UNITED STATES PATENT OFFICE.

URIEL YODER, OF NEAR WEST LIBERTY, OHIO.

PUMP ATTACHMENT FOR WINDMILLS.

SPECIFICATION forming part of Letters Patent No. 447,096, dated February 24, 1891.

Application filed October 11, 1890. Serial No. 367,776. (No model.)

To all whom it may concern:

Be it known that I, URIEL YODER, a citizen of the United States, and a resident of near West Liberty, in the county of Logan and 5 State of Ohio, have invented a new and useful Pump Attachment to Windmills, of which the following is a specification.

My invention relates to certain improvements in pump attachments to windmills.

10 Figure 1 is a front view; Fig. 2, a side sectional view.

In the usual mode of attaching the sucker-rod of a pump to the shaft of a windmill a loose pin is put through a hole in the top of 15 the sucker-rod and bottom of the shaft and fastened in place by running a piece of leather or a wedge through a hole in the end of the pin. This is both inconvenient and insecure, and a person is often at considerable trouble fitting the pin in the two holes. To obviate 20 this and render the attachment secure, I provide a hollow cast piece B, say a little over a foot long, having a hole in the top for permanent attachment by means of bolt N to 25 the shaft of the windmill. On the outside of piece B is bolted a spring D, carrying at its free end a jointed pin H, that plays freely in a hole S in the sucker-rod and holes Q R in the bottom end of piece B. On one side of 30 the piece B, near the bottom but above the pin H, are two lugs I, in which is journaled the cam-piece L. The shaft O has lever K secured on one end. The pin H is threaded at one end, and has a shoulder near the end. 35 It is attached to the spring D by inserting the threaded end through an opening in said

spring and against the shoulder, and screwing a nut on the end of the pin.

The operation is as follows: When it is desired to let the pump rest, the lever K is 40 thrown around in the position shown in dotted lines in Fig. 2, so that the cam-piece L will force the spring out from the side of the piece B and withdraw the pin H, so that its inner end will just rest in one hole in the 45 side of the piece B. The piece B is then free to work up and down on the sucker-rod C without operating it. When it is wished to run the pump, the handle K is thrown around in position shown in full lines in Fig. 2, when 50 the cam-piece L is brought into a vertical position and the spring D pushes the pin H through the hole in the top of the sucker-rod C and through the hole in the outer face of piece B, securely locking the sucker-rod and 55 shaft together. The cam-piece L is limited in its upward movement by the stop M on the inside of the spring D.

What I claim is—

1. In an attachment for coupling the sucker- 60 rod of a pump and the shaft of a windmill, the piece B, the spring D, pin H, the cam-piece L, and lever K, as and for the purpose set forth.

2. The attaching-piece B, the spring D, the 65 jointed pin H, playing through holes Q R S in piece B and sucker-rod C, the cam-piece L, and lever K, as and for the purpose set forth.

URIEL YODER.
